United States Patent

Des. 240,724

Patented July 27, 1976

240,724

PERFORATED PANEL

William G. Hale, Lake City, Ark., assignor to Gilbert International, Inc., Jonesboro, Ark.

Filed Nov. 12, 1974, Ser. No. 523,166

Term of patent 14 years

Int. Cl. D25—01

U.S. Cl. D25—39

FIG. 1

FIG. 1 is a front view of my novel perforated panel. The back view of the panel is substantially identical to the front view thereof;

FIG. 2 is an edge view of the panel;

FIG. 3 is a sectional view taken along line 3—3 in FIG. 1; and

FIG. 4 is a sectional view taken along line 4—4 in FIG. 1.

I claim:

The ornamental design for a perforated panel, as shown and described.
